UNITED STATES PATENT OFFICE.

RANSOM E. OLDS, OF DETROIT, MICHIGAN.

DESIGN FOR A VEHICLE-BODY FRAME.

SPECIFICATION forming part of Design No. 35,076, dated September 10, 1901.

Application filed June 5, 1901. Serial No. 63,811. Term of patent 14 years.

To all whom it may concern:

Be it known that I, RANSOM E. OLDS, a citizen of the United States, residing at Detroit, in the county of Wayne and State of Michigan, have invented and produced a certain new and original Design for Vehicle-Body Frames, of which the following is a specification, reference being had therein to the accompanying drawings, in which—

10 Figure 1 is a side elevation. Fig. 2 is a perspective view.

A is a body having an oblong rear portion and a forward portion consisting of an extension of the bottom of said oblong portion turned upward at its forward end.

15 C and D are pairs of parallel bars inclined downward respectively forwardly and rearwardly from the central portion of the body and at opposite sides thereof, and B represents connecting central portions of said bars parallel with the bottom of said body.

E represents cross-bars connecting the outer ends of the pairs of bars C C and D D.

The leading feature of the design is the oblong body having the upturned forward end and the pairs of parallel downwardly-inclined bars forward and rearward of the central portion of the body at opposite sides thereof, the outer ends of each pair of bars being connected by cross-bars and the space between the opposite bars of each pair being left open and unobstructed.

What I claim as my invention is—

The design for a vehicle-body frame, substantially as herein shown and described. 35

In testimony whereof I affix my signature in presence of two witnesses.

RANSOM E. OLDS.
